[57] **CLAIM**

The ornamental design for a treadmill housing, as shown and described.

DESCRIPTION

FIG. 1 is a perspective view of the treadmill housing showing my new design;

FIG. 2 is a perspective view of the treadmill housing of FIG. 1 from the opposed side thereof showing my new design;
FIG. 3 is a top view of the treadmill housing showing my new design on an enlarged scale from that shown in FIG. 1;
FIG. 4 is a bottom view of the treadmill housing showing my new design;

FIG. 5 is a front elevational view thereof; and,
FIG. 6 is a rear elevational view thereof.
